(57) **CLAIM**

The ornamental design of an offset display holder with C-channel, as shown and described.

DESCRIPTION

FIG. 1 is an enlarged perspective view taken from the front, top, right side of the offset display holder with C-channel showing my new design;

FIG. 2 is a top plan view of the offset display holder with C-channel of FIG. 1;

FIG. 3 is a bottom plan view of the offset display holder with C-channel of FIG. 1;

FIG. 4 is a front elevational view of the offset display holder with C-channel of FIG. 1;

FIG. 5 is a back elevational view of the offset display holder with C-channel of FIG. 1; and

FIG. 6 is a right side elevational view of the offset display holder with C-channel of FIG. 1, the left side elevational view being a mirror image thereof but otherwise identical;

FIG. 6a is an enlarged view of the right side elevational view of the offset display holder with C-channel of FIG. 1, the left side elevational view being a mirror image thereof but otherwise identical;

FIG. 7 is a perspective view taken from the front, top, right side of the offset display holder with C-channel of a second embodiment showing my new design, further views of the second embodiment not being shown as the further views are apparent from the views of FIGS. 1-6; and,

FIG. 8 is a perspective view taken from the back, top, right side of the offset display holder with C-channel of a third embodiment showing my new design, further views of the third embodiment not being shown as the further views are apparent from the views of FIGS. 1-7.

The broken lines shown in the figures represent portions of the offset display holder with C-channel that form no part of the claimed design.

1 Claim, 6 Drawing Sheets
